Application April 2, 1953, Serial No. 24,331
In Canada October 14, 1952

Term of patent 14 years

(Cl. D44—9)

To all whom it may concern:

Be it known that I, George Robert Palmeter, a citizen of Canada, residing at Kentville in the Province of Nova Scotia, Canada, have invented a new, original, and ornamental Design for a Cup or Similar Article, of which the following is a specification, reference being had to the accompanying drawing forming a part hereof.

Fig. 1 is a side elevational view of a cup, showing my new design;

Fig. 2 is a perspective view of the side opposite that shown in Figure 1; while

Fig. 3 is a perspective view of the side opposite the handle of that shown in Figure 1.

The cup presents a conventional appearance when viewed from the top.

I claim:

The ornamental design for a cup or similar article, as shown and described.

GEORGE ROBERT PALMETER.
